FRANK T. STUART, OF MAPLEWOOD, NEW JERSEY, ASSIGNOR TO THE R. NEUMANN HARDWARE CO., A CORPORATION OF NEW JERSEY

HINGE FOR SEWED-IN BAG FRAMES

Application filed July 10, 1926. Serial No. 121,617.

This invention relates to hinged frames for traveling bags to which the bag-body may be attached by continuous stitching.

The invention has for its principal object 5 to provide in combination with bag-frame sections for "sewed-in" bags, a novel construction and arrangement of hinge connection for so joining the frame sections that the bag body may be sewn to the entire frame structure by 10 an uninterrupted or continuous line of stitching.

Another object of this invention is to provide a novel construction of hinge connection for bag-frame sections, which is adapted to 15 maintain the frame sections in operative alignment, and reenforced against accidental distortion.

Other objects of this invention, not at this time more particularly enumerated will be 20 clearly understood from the following detailed description of the same.

The invention is clearly illustrated in the accompanying drawings, in which:—

Figure 1 is a side view of a bag-frame 25 provided with the novel construction of hinge connections made according to this invention, the bag-frame being shown in closed condition; Figure 2 is a plan view with the bag-frame shown in open condition; Figure 3 is 30 an inside end elevation of the novel hinge structure, drawn on an enlarged scale, in the position assumed when the frame sections are closed; Figure 4 is a similar view with the cooperating ends of the hinge plates shown 35 in vertical section; Figure 5 is a view similar to that of Figure 4, but with the hinge in the position assumed when the frame sections are open; Figure 6 is a fragmentary section, on an enlarged scale, taken on line 6—6 in Figure 2, but showing additionally the frame 40 covering leather and a portion of the bag-body as operatively assembled with the bag-frame; Figure 7 is a fragmentary plan view of the open frame sections, looking toward the 45 under exterior side thereof, i. e. with the frame inverted, illustrating the manner in which the stitching which fastens the bag body to the frame may be carried continuously past the hinge connection; and Figure 8 is a dia- 50 grammatic plan view of the open frame illustrating the continuous stitching path extending entirely around the same.

Similar characters of reference are employed in all of the hereinabove described views, to indicate corresponding parts. 65

Referring now to said drawings, the reference characters 10 and 11 respectively indicate the outer and inner frame-sections, with which are respectively connected by brackets 12 and 13, their respective side-frame sections 14 and 15, all so arranged that the side-frame sections are spaced from the outer and inner frame sections so as to provide an intervening sewing space 16. 70

Secured to opposing ends of the respective 65 side-frame sections 14 and 15 to pivotally interconnect the same together are the novel hinge connections made according to and embodying the principles of the present invention. Each such hinge connection comprises 70 a pair of hinge plates 17 and 18; one hinge plate, as 17, being secured to an end of the side-frame section 14, and the other hinge plate, as 18, being secured to the opposing end of the side-frame section 15. The hinge 75 plate 17 is provided at its free end with an angularly bent laterally oblique portion 19 terminating at its free end in a center perforate knuckle 20; in like manner, said hinge plate 18 is also provided at its free end with 80 an angularly bent laterally oblique portion 21, which terminates at its free end in a bifurcated perforate knuckle 22, adapted to straddle and be aligned with said center perforate knuckle 20 so that a hinge pintle 23 85 may be engaged through the thus aligned knuckles to pivotally connect the hinge plates in operative relation one to the other. As will be clearly evident from an inspection of Figures 1, 2, 6, 7 and 8 more especially, the 90 angularly bent laterally oblique portions 19 and 21 serve to inwardly off-set the hinge knuckles and pintle relative to the intervening sewing space 16 between the respective outer and inner frame sections and their 95 respective side-frame sections, thus leaving said intervening space 16, where the same passes the hinge connections, entirely free and unobstructed by any projecting portion or portions of said hinge connections, so that when 100

the bag body is sewn to the bag-frame, the work can be done by machine sewing or stitching around the entire frame and uninterruptedly past the points of pivotal connection of the frame sections one with another (as indicated by the dotted lines in Figure 8). This arrangement is of decided advantage when manufacturing the bag, since it not only saves time, but also produces a better and stronger attachment of the bag-body to the frame, with less likelihood of rips, especially at points adjacent to the bag-frame hinges, at which points the strains upon the sewn bag-body are usually greater than elsewhere around the frame. Another advantage of the novel hinge connections, whereby a continuous or uninterrupted sewing space 16 is provided around the entire extent of the whole bag-frame, is that the sewing or stitching may be started at any desired point relative to the whole bag-frame, and then continuously carried around the frame back to any such selected starting point.

In practice, the frame sections are usually provided with a covering of leather, as indicated at 24 in Figures 6 and 7, this covering extending around the frame sections and their side members and across the intervening sewing space 16, thus not only concealing the metallic frame, but providing a foundation coincident with the sewing space 16, through which the stitching 25 which attaches the bag-body 26 may be anchored.

Each hinge connection is provided with a means operative to yieldably hold the frame sections in extended open position to conveniently give access to the interior of the bag when the same is in opened condition. This means comprises, preferably in integral connection with the center knuckle 20 of the hinge plate 17, a cam projection 27 terminating in an angular stop face 28, and cooperating with said cam projection is a leaf-spring 29, which is suitably fixed relative to the opposite hinge plate 18, with its free resilient end portion 30 overlying the angularly bent laterally oblique portion 21 of the latter, and its extremity engaged with said cam projection 27. In operation, when the respective frame sections are swung apart, the turning of the center knuckle 20 causes the cam projection 27 to ride under and tensionally lift the resilient end portion 30 of said leaf-spring 29 until, upon attainment of full opening of the frame sections in relation one to the other, said resilient end portion drops upon and tensionally engages the stop-face 28 at the end of said cam projection, all as shown more especially in Figures 4 and 5 of the drawings. The pressure of said leaf-spring thus exerted upon the stop-face 28 tends to yieldably restrain the frame sections from movement to closed position, as will be evident.

Another advantage of the novel construc-

tion of hinge connections above described, lies in the fact that the angularly bent laterally oblique portions thereof not only inwardly off-set the interengaged knuckle connections out of the sewing path, but, furthermore, tend to stiffen the whole hinge connection against play, accidental distortion or displacement, and consequently thereby stiffens the frame members against possible accidental displacement from normal aligned cooperative relation one with the other.

Having thus described my present invention, I claim:

1. In a bag-frame, outer and inner frame sections adapted to telescope together, each having side-frame sections connected therewith so as to provide an intervening sewing space, hinge connections between the opposed terminal portions of said side-frames, each hinge connection comprising hinge plates respectively secured to opposite side-frames, transverse knuckle elements mutually aligned together, a pintle rivet pivotally connecting said knuckle elements, and inwardly extending laterally oblique portions downwardly inclined from the planes of said side-frame sections and interconnecting said knuckle elements and said hinge plates so as to off-set the former and their pintle rivets inwardly out of the line of said sewing space when said frame members are in opened horizontal extension.

2. In a bag-frame, outer and inner frame sections adapted to telescope together, each having side-frame sections connected therewith so as to provide an intervening sewing space, hinge connections between the opposed terminal portions of said side-frames, each hinge connection comprising hinge plates respectively secured to opposite side-frames, knuckle elements mutually aligned and pivotally connected together, laterally oblique portions intermediate said knuckle elements and said hinge plates adapted to off-set the former out of the line of said sewing space, a knuckle element of one hinge plate having an external cam portion terminating in an angular stop face, and a leaf-spring secured in connection with the other hinge plate and having its resilient free end disposed for cooperation with said cam portion and angular stop face to hold the hinge in open condition.

In testimony, that I claim the invention set forth above I have hereunto set my hand this 6th day of July, 1926.

FRANK T. STUART.
